UNITED STATES PATENT OFFICE.

WILLIAM A. HARDWICK, OF MEMPHIS, TENNESSEE, ASSIGNOR OF ONE-HALF TO
RICHMOND L. GRAVES, OF MEMPHIS, TENNESSEE.

CUT-OFF FOR BARREL-FILLING DEVICES.

1,064,208.

Specification of Letters Patent. Patented June 10, 1913.

Application filed November 22, 1909. Serial No. 529,344.

To all whom it may concern:

Be it known that I, WILLIAM A. HARDWICK, a citizen of the United States, residing at Memphis, in the county of Shelby 5 and State of Tennessee, have invented a new and useful Cut-Off for Barrel-Filling Devices, of which the following is a specification.

This invention has reference to improvements in barrel filling devices and its object is to provide a structure which will cut off the flow of liquid into barrels or other containers when the proper level therein has been attained.

15 In the present invention a valve is provided between a source of supply and the barrel or other container, in a conduit for the fluid, and this valve when opened is held in the open position against the force 20 tending to close it, the means for maintaining the valve open consisting of a suitable latch. When the fluid level has been reached at which point it is desired to cut off the flow of liquid, then the rise in the 25 fluid level causes the operation of the latch in a manner to release the valve to the force tending to close it, so that further flow of liquid into the barrel or container is arrested.

30 The invention will be best understood from a consideration of the following detailed description taken in connection with the accompanying drawings forming a part of this specification, in which drawings,—

35 Figure 1 is an elevation partly in section and partly broken away of the improved barrel filling and cut-off device. Fig. 2 is a detail section of a portion of the mounting for the valve stem. Fig. 3 is a view partly 40 in section showing the application of the filling device to ice-machine cans.

In the present device practically all the parts are stock parts and may be bought in the open market so that initially the device 45 may be constructed at small cost, and parts which must be manufactured specially are avoided. Therefore, the initial cost of the device is small and repairs may be readily made by the owner with parts purchasable 50 from any dealer in fittings for water or steam pipes.

Referring to the drawings there is shown a connection 1 in the form of a T herein-after referred to as the secondary T, the T

comprising a shank 50 and a head 51, the 55 head receiving at one end a pipe 2 constituting a float casing and having at an intermediate point an interior web 3 which though shown in the drawings as in one piece with the pipe may readily be made 60 separate therefrom. The pipe 2 is provided adjacent to the T 1 with external screw-threads as indicated at 4 to receive a spider 5 designed to engage the outer surface of the barrel when the pipe 2 is introduced into 65 the barrel through a bung-hole. The degree of entrance of the pipe 2 into the barrel is determined by the position of the spider 5 which may be screwed along the pipe 2 to any desired point within the range 70 of the screw threads 4. Above the web 3 the pipe 4 is provided with openings 6 for the passage of fluid from the T 1 to the interior of the barrel when the pipe 2 is introduced therein. Rising from the web 3 is a 75 tube or pipe 7 which may at the lower end be screwed into the web and this tube extends through the T into a cap 8 at the other end of the T. Extending through the tube 7 is a rod 9 passing into the pipe 2 below 80 the web 3 and there carrying a float 10 for which the pipe 2 constitutes a casing. This rod extends beyond the cap 8 and is screwed into a yoke block 11 to which it may be secured in any position of adjustment by the 85 lock nut 12. Rising from the T 1 is a post 13 to the upper end of which is pivoted a lever 14 connected at one end to the yoke block 11 and at the other end provided with a tooth 15. Screwed into the stem end of 90 the T 1 is a nipple 16 receiving at the other end one end of a valve casing 17 and this valve casing in turn is coupled to a pipe 18 which may lead to a suitable source of liquid supply, which liquid it is designed to ultimately deposit in the barrels or other containers. The valve casing 17 receives on one side a removable plug 19 and within the valve-casing 17 there is a flap valve 20 provided with a stem 21 one end of which extends through a packing gland 22, and exterior thereto has secured to it an arm 23 provided at the outer end with a pin 24 adapted to engage behind the tooth 15 of the lever 14. The valve 20 is under the normal control of a spring 25 connected at one end to the arm 23 and at the other end to the casing 17, this spring tending to move the valve 105

20 to the closed position. Secured to the T 1 is a handle 26 for the ready manipulation of the device.

The pipe 2 is introduced into a barrel 5 through the bung-hole thereof and the pipe 18 is connected to the source of liquid supply. The valve 20 may then be opened against the action of the spring 25 and locked in the open position by the engagement 10 of the tooth 15 with the pin 24 of the valve arm 23, the weight of the float 10 being sufficient to maintain the parts in this position. Liquid will flow through the pipe 18 thence to the valve casing 17 and through 15 the nipple 16 into the T 1 and thence by way of the pipe 2 and to the interior of the barrel through the opening 6 in said pipe.

The valve 20 is a flap valve and when open the flow of liquid through the valve casing 20 17 is practically unimpeded and the liquid may therefore flow to the barrel with the same freedom as though the valve were not present. When however, the desired liquid level has been reached within the valve then 25 the float 10 is lifted and the toothed end of the lever 14 depressed, thus releasing the arm 23 and the valve 20 is moved to the closed position by the action of the spring 25 augmented by the pressure of the liquid.

30 It will be observed that the valve stem 21 does not move longitudinally through the packing but only rotates therein so that leakage of the liquid is prevented for the wear on the packing is negligible.

35 In Fig. 3 there is shown a structure especially adapted for the filling of ice machine cans, one of which is indicated at 27 in the said figure. In general, the parts of the device are the same as already described with 40 relation to Figs. 1 and 2, but in place of the nipple 16 there is introduced another primary T 28 and between the head 52 of this T and the shank 23 of the secondary T 1' there is a solid plug 29 so that there is no 45 communication between the T 28 and the T 1'. Connected to the shank 54 of the T 28 is a pipe 30 of such length as to reach to the bottom of the can 27 and there this pipe is provided with openings 31 or any other 50 means of escape for the liquid passing through the pipe.

In order to prevent entrance of liquid into the pipe 2', which constitutes a casing and is mounted in one end of the head 55 of the secondary T , the openings 6 are omitted 55 in the structure of Fig. 3 but otherwise the pipe 2' is the same as shown in Fig. 1.

The structure may be centered in the can by means of diverging arms 32 designed to 60 engage the inner faces of the can, and these cans, as usually employed in ice-machines, are rectangular in cross section. The arms 32 may be arranged to engage the corners of the can and thus support the device in 65 centralized position in the can without dan-

ger of displacement during the filling of the can. At the same time such structure does not prevent the ready removal of the filling device from the can after the latter has been filled.

70 Because of the solid plug 29 no liquid passing through the pipe 18 will enter the pipe 2' or the T 1' but all the liquid will flow through the T 28 into the pipe 30 and so into the can 27. In Fig. 3, the pipe 2' 75 obviously constitutes a casing for the float 10. The pin 24 and the tooth 15 constitute interlocking elements, adapted to engage when the arm 23 and the lever 14 are properly positioned with respect to each other. 80 Owing to the fact that the valve casing 17 is rotatable upon the pipe 16, the arm 23 may be adjusted with respect to the lever 14, so that the tooth 15 will engage properly with the pin 24. Moreover, because the rod 85 9 is threaded into the yoke block 11, the float 10 may be adjusted with respect to the web 3, so that when the float 10 is raised, into abutment with the web 3, the pin 24 will be moved out of engagement with the tooth 90 15. It will be seen, therefore, that by rotating the valve casing 17 upon the pipe 16, the pin 24 and the tooth 15 may be positioned for engagement with each other; and by rotating the rod 9 in the yoke block 11, 95 the float 10 will be so positioned with respect to the web 3 that the raising of the float 10 will with certainty break the interlocking relation between the pin 24, and the tooth 15.

100 What I claim is:—

1. In a device of the class described, a float casing; a supply pipe; a connection uniting the float casing with the supply pipe; a float in the casing, there being a web in the casing constituting a stop for the float; a rod connected with the float and extended through the connection; a lever fulcrumed intermediate its ends upon the connection; a valve casing rotatable upon the supply pipe; a valve in the valve casing; an arm secured to the valve; there being interengaging elements upon the arm and the lever, the rotation of the valve casing serving to adjust the arm with respect to the lever to permit said elements to interengage; the lever being tiltable to break the engagement between said elements; a yoke pivoted to the lever, the rod being threaded into the yoke, for longitudinal adjustment therein, whereby, when the float is elevated into engagement with the web, the engagement between the interengaging elements of the arm and the lever will be broken.

110 2. In a device of the class described, a primary T and a secondary T , the shank of the secondary T being alined with the head of the primary T ; a solid plug inserted into one end of the head of the primary T and into the shank of the secondary T ; a pipe depending from the shank of the pri- 115 120 125 130

mary T and adapted to extend toward the bottom of the receptacle to be filled; a casting in one end of the head of the secondary T; a cap upon the other end of the head of the secondary T; there being a web extended across the valve casing; a pipe connecting the web with the cap; a rod slideable in the last specified pipe; a float connected with the rod and located below the web; a valve connected with the other end of the head of

the primary T; and means connected with the rod for maintaining the valve releasably open when the float is depressed.

In testimony that I claim the foregoing as my own, I have hereto affixed my signature in the presence of two witnesses.
